PACKING MACHINE

Charles L. Doney, San Pedro, Calif.

Application October 11, 1937, Serial No. 168,527

5 Claims. (Cl. 226—96)

The invention relates to a packing machine and more particularly to a machine for use in the mechanical packing of fish. This work is generally effected by hand and is a slow, disagreeable, tedious task necessitating long hours of continuous work.

The primary object of the invention is the provision of a machine of this character, wherein fish, after being cleaned, can be mechanically 10 and automatically cut and packed in a fast economical way reducing the spoilage to a minimum.

Another object of the invention is the provision of a machine of this character, wherein the fish will be packed into cans, these after the packing 15 are ready for the steam boxes where they are cooked and sent to the sealing machine, the lids being put on and the cans sealed, the machine being novel in its entirety and assures a continuity of packing operation.

20 A further object of the invention is the provision of a machine of this character, which is simple in construction, thoroughly reliable and efficient in operation, automatic in the working thereof, readily and easily adjusted and inexpensive to manufacture and install.

With these and other objects in view, the invention consists in the features of construction, combination and arrangement of parts as will be hereinafter more fully described, illustrated in 30 the accompanying drawings, which disclose the preferred embodiment of the invention and pointed out in the claims hereunto appended.

In the accompanying drawings:

Figure 1 is a fragmentary top plan view of a 35 machine constructed in accordance with the invention.

Figure 2 is a vertical sectional view thereof.

Figure 3 is a sectional view on the line 3—3 of Figure 2 looking in the direction of the arrows.

40 Figure 4 is a sectional view on the line 4—4 of Figure 2 looking in the direction of the arrows.

Figure 5 is a sectional view on the line 5—5 of Figure 2 looking in the direction of the arrows.

45 Figure 6 is a fragmentary sectional view through the can carrier.

Figure 7 is an elevation of the cam track of the machine.

Similar reference characters indicate corresponding parts throughout the several views in 50 the drawings.

Referring to the drawings in detail, A designates generally a portion of a horizontal support in effect creating a stand and from which rises perpendicularly a stationary shaft 10, being made 55 secure in the support in any suitable manner and

has formed near its lower end a circular bed flange 11 provided at its under face with nibs 12 which bite into the support while threaded on the lower end of said shaft is a nut 13, this fastening the shaft securely.

Rotatable about this shaft 10 is a turntable 14 forming a can carrier, being of substantially disk shape and having peripherally thereof can seats 15, these opening outwardly and releasably clamp therein can bodies 16 which are devoid of lids or covers and are adapted to be filled or packed in the operation of the machine.

The turntable 14, which is rotated in any desirable manner, has an upstanding central hub 17 externally threaded at 18 for an adjustable 15 collar 19 and this hub is accommodated in a columnar centrally located hub portion 20 formed interiorly of a rotatable cylinder 21, being in resting position upon the collar 19 which regulates the spaced relationship thereof to the table 14. 20 The columnar hub portion 20 of the cylinder 21 is splined or keyed at 22 with the hub 17 so that the turntable and said cylinder 21 rotate in unison with each other.

Formed at the perimeter of the cylinder 21 are 25 vertically disposed cylinders or tubular columns 23, these being open at opposite ends and are aligned with the seats 15 in the turntable 14 while reciprocatingly movable within the cylinders or columns 23 are packing pistons or plungers 24, the stems 25 of which at their upper end portions are formed with elbows 26, these slidably fitting in runners 27 operating in vertical slotted guides 28 fixed to and rising above the upper open end of the cylinder 21. The runners 30 35 27 operate within the slots of the guides 28 vertically while the elbows 26 at their ends carry rollers 29, these movably fitted within a substantially oval shaped cam track 30 armed at 31, the latter being fitted at 32 to the stationary shaft 10 40 thus stationarily holding the track above the cylinder 21. The plungers or pistons 24 operating in the track 30 during the rotation of the cylinder 21 reciprocate within the cylinders 23 for packing operation. During rotation of said cylinder 21, 45 these pistons or plungers 24 move outwardly of the cylinders 23 at one side of the cylinder 21 so that clean fish can be fed into the cylinders at such side from a depository serving as a receiver for the fish before the packing operation and 50 the fish within this depository can be mechanically or manually removed therefrom for the placing of such fish into the cylinders 23 from which have been removed the plungers or pistons 24 in the cycle of operation of the machine.

The track 30 has high and low stretches thereto and at the high stretch of the same a retaining member 33 is provided thereon to hold the members 29 within the track and to cause the plungers or pistons 24 when without the cylinders 23 to be moved laterally in the runners 27 fitting the guides 28 and thus avoiding obstructing access to the cylinders 23 at the filling side of the cylinder 21 for the packing of fish within these cylinders. The high and low stretches of the track 30 effect reciprocation of the pistons or plungers 24 in the cycle of rotation of the cylinder 21. When the pistons or plungers 24 are automatically lowered in the cylinders 23, the material therein is forced and packed into the cans 16 upon the turntable 14, the fish being admitted into the cans through the lower open ends of said cylinders 23 during rotation thereof simultaneously with the rotation of the turntable 14, these being rotatable in unison with each other.

At one side of the cylinder 21 and fixed to an operating shaft 34 is a disk-like rotary cutter 35 which operates between a can 16 upon the turntable 14 and the lower open end of a cylinder 23 in the cylinder 21, this cutter 35 being horizontally arranged and functions to cut the fish to avoid surplus filling of the cans 16, the cutter 35 being located at the packing side of the cylinder 21 and its shaft 34 is power driven in any suitable manner.

In the operation of the machine the dressed fish are delivered into the cylinders 23 at the filling side of the cylinder 21, either manually or mechanically, and as the turntable 14 and cylinder 21 rotate in unison with each other, the filled cylinders 23 through the action of the plungers or pistons 24 will deliver the fish successively into the cans 16 on the turntable 14 while the cutter 35 severs superfluous fish at the top open ends of the cans to avoid overfilling of the latter. The packed cans of fish are taken from the machine by successive removal from the turntable 14 and empty cans substituted so that in this manner fish can be mechanically and automatically packed in a fast economical way in the cans 16, reducing the spoilage to a minimum and such filled cans after passing the cutter are removed from the turntable and conveyed from the machine to steam boxes where the same are cooked and thereafter sent to a sealing machine where the lids are put on and the cans sealed, the packing and filling operations of the machine being continuous in the working thereof.

The cylinder 21 is adjustable with relation to the turntable 14 in conformity with the sizes of the cans 16 to be filled and packed.

The shaft 34 carries an adjustable collar 36, which enables vertical adjustment of the cutter 35 in conformity with the adjustment of the relationship of the turntable and cylinder. It is, of course, understood that a suitable shelving concentric to the shaft 10 and supported from the

support to be disposed beneath the open ends of the cylinders or columns 23 for the closing of these lower ends excepting that cylinder or column having its lower end disposed over the rotary cutter 35 is present in the machine and in this way the filling of these cylinders or columns 23 cannot drop out of the same during the cycle of operation of said machine. 5

What is claimed is:

1. A machine of the character described comprising a turntable having peripheral seats for cans, a cylinder turnable with the table and having cylinders aligned with the seats, pistons operating within the cylinders and movable without the same, trackage effecting movement of the pistons, and a cutter operating between the turntable and said cylinder. 10

2. A machine of the character described comprising a turntable having peripheral seats for cans, a cylinder turnable with the table and having cylinders aligned with the seats, pistons operating within the cylinders and movable without the same, trackage effecting movement of the pistons, a cutter operating between the turntable and said cylinder, and means for adjusting 15 the cylinder with relation to the turntable. 20

3. A machine of the character described comprising a turntable having peripheral seats for cans, a cylinder turnable with the table and having cylinders aligned with the seats, pistons operating within the cylinders and movable without the same, trackage effecting movement of the pistons, a cutter operating between the turntable and said cylinder, means for adjusting the cylinder with relation to the turntable, and means for adjustment of the cutter with relation 30 to the cylinder and turntable. 35

4. A machine of the character described comprising a turntable having peripheral seats for cans, a cylinder turnable with the table and having cylinders aligned with the seats, pistons operating within the cylinders and movable without the same, trackage effecting movement of the pistons, a cutter operating between the turntable and said cylinder, means for adjusting the cylinder with relation to the turntable, means for adjustment of the cutter with relation to the cylinder and turntable, and guides associated with the cylinder for the said pistons. 40

5. A machine of the character described comprising a turntable having peripheral seats for cans, a cylinder turnable with the table and having cylinders aligned with the seats, pistons operating within the cylinders and movable without the same, trackage effecting movement of the pistons, a cutter operating between the turntable and said cylinder, means for adjusting the cylinder with relation to the turntable, means for adjustment of the cutter with relation to the cylinder and turntable, guides associated with the cylinder for the said pistons, and a support for the trackage. 50
